UNITED STATES PATENT OFFICE.

HENRY H. HOLCOMBE AND WILLIAM A. BARTSCHMID, OF MARSHALL, TEXAS.

HYDROCARBON BURNER.

Application filed June 2, 1926. Serial No. 113,214.

Our present invention pertains to hydrocarbon burners and contemplates the provision of a burner adapted to facilitate the combustion of commingled oil and steam, 5 the said burner being simple and inexpensive in construction, being made up of elements adapted to be readily assembled and as readily disconnected, and being so characterized that the commingled steam and 10 oil is supplied with an abundant quantity of air with a view to supporting combustion and in that way increasing the efficiency of the burner.

To the attainment of the foregoing, the 15 invention consists in the improvement as hereinafter described and definitely claimed.

In the accompanying drawings, forming part of this specification:—

Figure 1 is a longitudinal vertical section 20 illustrative of the preferred embodiment of our invention.

Figure 2 is a top plan view of the same.

Figure 3 is an end elevation taken from a view point at the right of Figure 2.

Similar numerals of reference designate 25 corresponding parts in all of the views of the drawings.

Among other elements our novel burner comprises a tube section 1, which is preferably an appropriate length of type and is 30 exteriorly threaded at its heel end as designated by 2. The said tube 1 is the outer tube of the burner and encloses an inner tube 3 and a central tube 4, the tubes 1, 3 35 and 4 being of the relative diameters illustrated so that a space 5 is formed about the tube and between the same and the other tube 1, while a space 6 is formed about the central tube 4 and between said tube 4 and

40 the tube 3; the forward end of the outer tube 1 being open as is also the forward end of the central tube 4 and the forward end of the tube 3, and the forward ends of the said spaces being also open. The tube 3 is 45 threaded at its heel end as designated by 7 and the central tube 4 is threaded at its heel or rear end as designated by 8, and it will be noted that the central tube 4 extends beyond the ends of the tube 3, and this 50 about the proportional distance illustrated in Figure 1. An elbow 9 is turned on the rear end of the tube 4 and is adapted to be connected by a suitable conduit, not shown, with the source of hydrocarbon fuel supply.

55 The rear threaded portion of the tube 4 also serves for the connection of the rear por-

tion of a hollow head 10, the intermediate portion of which is turned on and supported by the tube 3, while the forward portion of said head is threaded and turned on and connected to the rear end of the outer tube 1. Thus it will be understood that the hollow head 10 effects connection of the central tube 4 and the intermediate tube 3 with the outer tube 1, and also serves to maintain 60 the several tubes 1, 3 and 4 in the spaced arrangement illustrated in Figure 1, and necessary to the proper operation of our novel burner.

The hollow head 10 is provided at 11 70 with an arm for the connection of a conduit, not shown, designed to lead from a source of steam supply, and said hollow head is provided at 12 with oppositely directed lateral arms which terminate in upstanding portions 13, designed to conduct air from the interior of a fire box where the air is necessarily of a comparatively high temperature to the heel end of the outer tube 1 so that the suction maintained by the forcible passage 80 of steam through the tube 3 and between the wall of said tube 3 and the central tube 4 will have the effect of drawing air into the steam and oil with the result that the combustion of the fuel will be maintained at a 85 high degree of efficiency.

In the above connection, it will be noted that the steam will be jetted forwardly to the forward end of the tube 4 and about said tube 4 in annular fashion so that the fuel or 90 oil will be adequately vaporized in the forward end or at the forward end of the outer tube 1 at which point an adequate amount of air will at all times be supplied to the burning fuel.

We have specifically described the construction and relative arrangement of the parts embraced in the present and preferred embodiment of our invention in order to impart a full, clear and exact understanding of the said embodiment. We do not desire, however, to be understood as limiting ourselves to the precise structure disclosed, our invention being defined by our appended claims within the scope of 100 which modifications may be made without departure from our invention.

The burner is designed to save fuel and the embodiment of the invention illustrated herein is preferred because it assures heating 110 of both air and oil before combustion.

Having described our invention, what we

claim and desire to secure by Letters Patent, is:—

1. In a burner and in combination, a tube exteriorly threaded at its rear end, a central tube of comparatively small diameter arranged longitudinally in the first-named tube and extending rearwardly from the same and provided with an exteriorly threaded rear portion, and an intermediate tube arranged in the first named tube and spaced therefrom and also arranged about the central tube and spaced therefrom and extending rearwardly from the first-named tube to an intermediate point in the length of the central tube, and a hollow head threaded at its rear side on the threaded portion of the central tube and also threaded at an intermediate point on the rear end of the third named or intermediate tube and further threaded at its forward side on the rear end of the outer or first-named tube and having oppositely directed lateral arms at substantial right angles to the several tubes and adapted for the supply of air to the rear end of the outer tube.
2. In a burner and in combination, a tube exteriorly threaded at its rear end, a central tube of comparatively small diameter

arranged longitudinally in the first-named tube and extending rearwardly from the same and provided with an exteriorly threaded rear portion, and an intermediate tube arranged in the first named tube and spaced therefrom and also arranged about the central tube and spaced therefrom and extending rearwardly from the first-named tube to an intermediate point in the length of the central tube, and a hollow head threaded at its rear side on the threaded portion of the central tube and also threaded at an intermediate point on the rear end of the third named or intermediate tube and further threaded at its forward side on the rear end of the outer or first-named tube and having oppositely directed lateral arms at substantial right angles to the several tubes and adapted for the supply of air to the rear end of the outer tube; the said lateral arms of the hollow head being equipped with upturned open terminals for the admission of air from the interior of a firebox to the said arms.

In testimony whereof we affix our signatures.

HENRY H. HOLCOMBE.
WILLIAM A. BARTSCHMID.
